WRIST-TYPE MEMORANDUM PAD

Dana W. Canfield, Chico, Calif.

Application July 24, 1936, Serial No. 92,426

2 Claims. (CL 281--1)

This invention relates to a novel utility memorandum pad of a so-called wrist type for personal adoption and use susceptible of being conveniently worn on the wrist of the user to expedite 5 jotting down notes with a pencil in an obvious manner.

Admittedly, the idea of using wrist straps for holding various accessories in place is not new. Moreover, there is nothing broadly new in the 10 idea of constructing a miniature memorandum or notation pad applicable to the wrist or hand for expeditious usage. It follows, therefore, that the present invention has to do with the addition to this particular line of endeavor of a novel 15 utility type memo pad miniature in character, held in place by a suitable wrist strap, but possessed of features of distinction and refinement making it more aptly fitted for the specific purposes intended.

One feature of the unique assemblage is the 20 adoption of a wrist strap satisfactorily cooperable with the miniature paper pad as to permit the pad to be renewed from time to time so that the perfected principles of the idea of the invention 25 may be adequately fulfilled.

Specific structural novelty may be found to 30 exist in the special coordination of the renewable pad and wrist strap assembly, though novelty in the pad itself appears to be present to the extent 35 of directing justified attention to the newness of the parts separately and collectively.

Other features and advantages may become 40 apparent from the following description and drawings.

In the drawings, wherein like numerals are 45 employed to designate like parts throughout the views:

Figure 1 is what may be called a plan or an 50 elevational view showing how the complete attachment is applied to the wrist of the wearer for convenient use.

Figure 2 is a view of the attachment per se 55 showing it removed from the wrist and disclosing how the strap is slidably and detachably connected with the pad.

Figure 3 is an edge view of the pad showing 60 the strap connecting means from another viewpoint.

Figure 4 is a perspective view of one of the 65 double tab-equipped leaves of the multiple leaf memorandum pad.

Figure 5 is an exaggerated fragmentary sectional view showing how the tabs are stapled on 70 the backing member, and how the substantially

U-shaped member or bail is fastened to the rivet to accommodate the wrist strap.

Figure 6 is a perspective view of the so-called bail.

Figure 7 is a fragmentary plan view of a modified type of wrist strap with the pad removed.

Figure 8 is an enlarged detail section on the plane of the line 8--8 of Figure 7.

The miniature pad is standardized in construction and here designated as a unit by the numeral 9. It comprises a cardboard backing sheet or member 10, this being of general rectangular form and provided at opposite ends with anchoring extensions or riveting ears 11. Superimposed upon this in customary stacked relationship are the individual tearable memorandum sheets of paper 12. These have corresponding configuration and at the ends are provided with retention tabs 13 joined to the body portion by scored lines 14. The tabs 13 are secured by rivets 15 to the extensions 11. Thus, after a notation is jotted down in pencil on the top sheet, one corner portion thereof can be peeled up with the finger and the rectangular portion torn off leaving the tabs 13 in place. As the sheets 12 are individual, it is obvious that they can be easily removed and filed away in one pocket or elsewhere for future reference purposes. Each pad also includes a pair of U-shaped wire members 16 conveniently called bails. These are in effect strap loops and are provided with eyes 17 on the ends of the arm portions secured by the clenched terminals 18 of the rivets as shown in exaggerated form in Figure 5. Thus, the simple strap can be passed through these strap loops 20 or bails 16 to complete the assembly. The strap may be provided with a buckle 19, the strap itself being differentiated by the numeral 20.

In some instances instead of extending the wrist strap through the shackling bails or loops 25 40 16, I have found it expedient and practicable to utilize a special wrist strap of the type shown in Figures 7 and 8. Here the strap is merely differentiated for convenience by the numeral 21 and has an enlarged adapter end portion 22 45 which conveniently seats itself upon the wrist as is obvious. This is provided with an appropriate strap and retaining buckle 23. The main feature, however, is in the provision of the longitudinally spaced rivets 24 connected thereto and provided 50 with oppositely extending hooks 25 which may be called keepers for the shackles 16. Under this arrangement the pad is simply placed between two longitudinally spaced keeper hooks 25 and the two end shackles 16 are hinged outwardly and 55

connected with the hooks. Fundamentally, however, the arrangement is the same in the sense that the wrist strap is detachably connected with the retaining shackles or bails 16.

5 It is obvious that an article of this type is satisfactorily usable in innumerable lines of endeavor. It was perfected with the thought in mind of providing a convenient accessory to be worn by gasoline dispensing attendants, enabling them to jot down notes calculating charges, or to make notes for charge accounts to special customers, and so on. In this particular line of endeavor as well as in many others clerks are depended upon to retain considerable details in mind and frequently the rush of subsequent customers makes it impracticable to enter charges and the like in the book. Consequently, the provision of a unique memorandum pad of the type herein disclosed constitutes a convenient 10 20 worthily endorsed appliance.

Not only is the device an innovation in the line of endeavor above specified, but it is susceptible of adequate and efficient use as a golf scorer. That is to say, it may be conveniently 25 worn on the wrist of the golf player and thereby be in readiness for convenient use in tallying golf scores.

It is thought that the description taken in connection with the drawings will enable a clear 30 understanding of the invention to be had. Therefore, a more lengthy description is thought unnecessary.

While the preferred embodiment of the invention has been shown and described, it is to be understood that minor changes coming within the field of invention claimed may be resorted 35 to if desired.

I claim:

1. A wrist-type memorandum pad comprising a backing member of relatively rigid material formed at opposite ends with special adapter extensions, a memorandum pad composed of a plurality of individual memorandum sheets 5 stacked upon one another and assembled on said backing member, said sheets being provided with anchoring tabs corresponding to said extensions, said tabs being connected with the body portions of the sheets through the instrumentality of 10 score lines, rivets passing through the respective sets of tabs and extensions, the rivets being of general U-shaped form and the free ends thereof being fashioned into retention eyes, and a pair of strap accommodation balls of general U-shaped 15 form having the free ends of their arms provided with eyes hingedly connected with said first-named eyes.

2. A wrist-type memorandum pad comprising a relatively rigid substantially rectangular backing and base forming member, said member being provided on opposite edges with outstanding relatively narrow tongue-like extensions, a plurality of individual detached memorandum sheets disposed in stacked superimposed relation, said sheets corresponding in shape and proportions to said backing member, said sheets being provided on opposite ends with retaining tabs, said tabs being detachably connected with the body portion of said sheets by score lines, said tabs being positioned in alignment with the aforementioned extensions, fasteners passing through the respective sets of tabs and extensions, said fasteners projecting beyond adjacent surfaces of said extensions, and a pair of strap accommodation units hingedly connected with the projecting portions of said fasteners.

DANA W. CANFIELD.
